BULLET STOP

Arthur D. Caswell, Anoka, Minn.

Application May 15, 1933, Serial No. 671,128

3 Claims. (Cl. 124—15)

My invention relates to bullet stops and has for its object to provide a simple and effective device which will function positively and effectively.

An object of the invention resides in providing 5 a bullet stop which may be constructed as an individual unit and which may be utilized in conjunction with other units to build up a battery of bullet stops.

A still further object of the invention resides 10 in constructing the bullet stop with two deflector plates arranged one above the other and inclined so as to cause the downward discharge of bullets when the bullets strike the same.

An object of the invention resides in providing 15 a downwardly projecting lip at the lower end of each deflector plate from which the bullets are discharged.

Another object of the invention resides in placing 20 a receptacle below said discharge lip and into which the bullets are discharged after the force of the bullets has been spent.

A still further object of the invention resides 25 in arranging the uppermost bullet stop with the lip thereof projecting rearwardly of the bullet stop immediately below it so as to cause the discharge of bullets from said upper deflector plate directly into the receptacle.

Another object of the invention resides in providing 30 vertically extending guides and in slidably positioning one of the deflector plates for vertical movement relative to the guide.

A feature of the invention resides in employing 35 posts, preferably of T-shaped or angular cross section with the flanges thereof facing one another and lying in a common plane to support said deflector plates, the flanges of said posts forming the guides for the movable deflector plates.

An object of the invention resides in providing 40 each of the deflector plates with laterally disposed flanges and in further providing means on said flanges for engagement with the flanges of the posts.

Another object of the invention resides in attaching 45 pulleys to the upper ends of the posts and in providing cables passing over said pulleys, said cables being each secured at one end to one of said deflector plates and having attached to their other ends counter weights.

A feature of the invention resides in attaching 50 each cable to a part of the structure for guiding the deflector plate along the guides.

An object of the invention resides in extending 55 a rod across the flanges of each deflector plate near the upper ends thereof, said rods serving as supports for the targets.

Other objects of the invention reside in the novel combination and arrangement of parts and in the details of construction hereinafter illustrated and/or described.

In the drawings:

Fig. 1 is an elevational view of a portion of an installation illustrating an embodiment of my invention.

Fig. 2 is a vertical sectional view taken on line 2—2 of Fig. 1.

Fig. 3 is a fragmentary plan sectional view taken on line 3—3 of Fig. 1.

Fig. 4 is a fragmentary plan sectional view taken on line 4—4 of Fig. 1.

Fig. 5 is a fragmentary elevational view of the 15 guide structure utilized with one of the deflector plates.

Fig. 6 is a fragmentary sectional view similar to Fig. 3 taken on line 6—6 of Fig. 1.

My invention proper may be installed in base- 20 ments or other localities where the space is con- fined and where protection is desired. In the

drawings I have shown a portion of a building having a floor 10 and a ceiling 11, said ceiling comprising joists 12 arranged at spaced inter- 25 vals and covered by flooring 13 forming the floor of an upper story. These joists serve to support the posts used with the invention. It can readily be comprehended, however, that where joists are not available suitable auxiliary supports may 30 be erected so that the invention may be installed in any type of building regardless of the construction thereof or regardless of the ceiling height of the room in which the bullet stop is to be used.

My invention proper comprises a plurality of 35 metal posts 14, 15, 16 and 17 which are preferably T-shaped in cross section having aligning flanges 18 and 19 and outwardly extending flanges 20.

These posts are preferably arranged with the 40 flanges 18 and 19 in a common plane. Where the installation is being made in a building such as

described, the posts 14, 15, 16 and 17 are some- 45 what longer than the height between the floor 11 and the undersides of the joists 12 and the upper ends of the said posts are in such case bolted directly to one of the joists 12 through bolts 21.

The lower ends of these posts are bolted by means of bolts 23 to a horizontally extending angle 22, which angle is in turn anchored to the 50 floor 10 in any suitable manner. Between the various posts 14, 15, 16 and 17 are disposed iden- 55 tically constructed deflector plates 24, 25, 26, 27, 28 and 29, a detailed description of one of which will suffice for all.

The deflector plate 26 is constructed of sheet steel and consists of a plate-like portion 30 which has bent downwardly therefrom along the two lateral edges thereof, flanges 31 and 32. These flanges 31 and 32 fit snugly in between the facing edges of the flanges 18 and 19 of posts 15 and 16. At the lower end of the plate portion 30 is a curved depending lip 33, the lower marginal portion of which extends substantially vertically when the deflector plate is properly mounted between the two posts 15 and 16.

The deflector plate 26 is arranged in inclined relation with the lip 33 at the lower end thereof farthest from the shooting booth and with the plate portion 30 inclining upwardly and toward the marksman.

The deflector plate 26, like its companion upper plates 24 and 28, is held in position through two pairs of clip angles 34 and 35 which are welded to the flanges 31 and 32 along lines 135. These clip angles are arranged in spaced relation, one pair thereof receiving the flange 19 of the post 15 and the other pair receiving the flange 18 of post 16, said clip angles being angularly disposed with respect to the flanges 31 and 32 so as to hold the deflector plate in proper inclined position. Bolts 36 passing through the outstanding flanges 37 of the clip angles 34 and 35 and through the flanges 19 and 18 of the posts 15 and 16 secure the said plate 26 to said posts.

The deflector plate 27, like its companion lower plates 25 and 29, is applied to the supporting posts in a manner somewhat similar to the deflector plate 26. To each of the flanges 31 and 32 of said plate 27 are secured a pair of clip angles 38 and 39 which are welded to the flanges 31 and 32 along lines 40. These clip angles are spaced as indicated at 41 in Fig. 5 to form a groove for the reception of the flanges 19 and 18 of posts 15 and 16. The grooves 41 are of such width as to permit the deflector plate 27 to slide freely in a vertical direction along said flanges which serve as guides for slidably supporting the same.

For the purpose of supporting the deflector plate 27 in proper position, the flange 42 of clip angle 39 on flange 31 is extended above the upper surface of the plate-like portion 30 of said deflector plate. This extended part of said angle 39 is formed with an opening 43 in which is secured the end 44 of a cable 45. Cable 45 extends upwardly along the rearward face of the post 15 and passes over a pulley 46 secured to said post. This pulley is rotatably mounted on a stud shaft 65 which is formed with a threaded end 66 reduced in diameter. This portion of the stud extends through a bracket 67 secured to flange 20 of post 15 and is held in place thereon through a nut 68. A counter weight 47 attached to the end 48 of the cable 45 serves partly to counterbalance the weight of the deflector plate 27. A similar cable is secured to the corresponding clip angle attached to flange 32 of plate 27 and passes over a similar pulley carried by post 16. This cable in turn has attached to it a counter weight identical with the weight 47. The two counter weights substantially balance the weight of the deflector plate 27, whereby the said deflector plate may be held in any adjusted position with respect to the posts 15 and 16. The lower deflector plates 25 and 29 are supported in a manner similar to that of said deflector plate 27. To the clip angles 38 thereof are attached cables 49 which extend along the forward surfaces of posts 14, 15, 16 and 17, and which pass over pulleys 50 mounted on the

flanges 18 and 19 of said posts. These pulleys are journaled on stud shafts 69, similar to shafts 65, which are directly attached to the said flanges of the posts. Counter weights 51 are secured to the ends of the cables 49.

With each of the deflector plates is employed a target 52 which may be constructed of paper or any other suitable material. This target has secured to it two hangers 53 and 54 which are constructed at their upper ends with hooks 55. These hooks are adapted to hook over a rod 56 extending between the flanges 31 and 32 and secured thereto. By means of this construction the targets 52 on the lower deflector plates are raised and lowered with said plates while the said plates are manipulated to accommodate the shooting positions assumed by the marksman.

The bullet stop is provided with a receptacle for bullets which is indicated in its entirety at 57. Receptacle 57 consists of walls 58, 59, 60 and 61. This receptacle 57 is open at the top and may be constructed without a bottom and may rest directly upon the floor of the building in which the bullet stop is installed. Said structure encloses the posts 14, 15, 16 and 17 and may also enclose the angle 22. Within the receptacle 57 sand is placed as indicated at 62.

The invention is used and operates as follows: When the marksman desires to shoot while standing, the lower deflector plates are raised so that the relation thereof with respect to the fixed upper plates is the same as that illustrated at the right and at the left of Fig. 1. The marksman then shoots at the desired target. The bullets pass through the target and strike the planiform portion 30 of the deflector plate carrying the target, said bullet being deflected downwardly and rearwardly and thence finally downwardly by the lip 33 into the sand 62 in the receptacle 57. When the marksman wishes to shoot from a prone position, one of the lower deflector plates is lowered into the position in which deflector plate 27 in Fig. 1 is shown. The marksman may then shoot at the target carried thereby and the bullets, on striking said deflector plate, will be deflected downwardly and into the receptacle 57. Due to the fact that the lips of the uppermost deflector plates are rearwardly from those of the lowermost deflector plates, each set of deflector plates causes the discharge of bullets separately into the receptacle without interference and without the bullets from the uppermost deflector plate striking the lowermost deflector plate. When the marksman wishes to shoot from a kneeling position, one of the lower deflector plates carrying the particular target to be used may be elevated or lowered, as the case may be, into the proper position.

My invention is exceedingly simple and is positive in action. Each of the deflector plates can be constructed from sheet metal bent into the desired form and without special tools or equipments. The deflector plates are adjustable to accommodate different postures of the marksman. Due to the fact that the lower deflector plates may be adjusted, the bullet stop may be employed for all positions of the marksman without requiring the entire surface of the wall in back of the bullet stop to be completely protected. By discharging the bullets in the sand contained within the receptacle for bullets, a part of the momentum of the bullet is absorbed when the bullet strikes the sand so that it becomes unnecessary to absorb all of the energy of the bullet at

the deflector plate. By arranging the upper deflector plates, bullets are prevented from striking the lower deflector plates upon being discharged from the upper plates. By means of the pulleys 5 and counter weights, the deflector plates may be easily and quickly adjusted from one position to another and require no locking means to hold them in any particular position. With my construction, the bullet stop may be built in units 10 and additional units added as desired to build up a bullet stop of any desired width and to accommodate any number of marksmen.

Changes in the specific form of my invention, as herein disclosed, may be made within the scope 15 of what is claimed without departing from the spirit of my invention.

Having described my invention, what I claim as new and desire to protect by Letters Patent is:

1. A bullet stopping device for use with targets 20 disposed one above the other, said device including upright supporting means, and deflector plates mounted thereon, one above the other, there being one deflector plate for each target, a bullet receptacle common to said deflector plates, said receptacle being located beneath the lowermost plate, each deflector plate being inclined 25 downwardly from the front thereof and having a lip at its lower end with a downwardly extending discharge surface for directing bullet 30 fragments downwardly into said receptacle, the lip of the lowermost deflector plate being disposed forwardly of the lip of the deflector plate thereabove, whereby bullet fragments discharged from said latter plate will be directed clear of 35 said lowermost plate.

2. A bullet stopping device for use with targets

disposed one above the other, said device including upright supporting means, and deflector plates mounted thereon, one above the other there being one deflector plate for each target, one of the plates being supported for vertical 5 adjustment and having means for supporting its respective target in front thereof, a bullet receptacle common to said deflector plates, said receptacle being located beneath the lowermost plate, each deflector plate being inclined downwardly from the front thereof and having a lip 10 at its lower end with a downwardly extending discharge surface for directing bullet fragments downwardly into said receptacle, the lip of the lowermost deflector plate being disposed forwardly of the lip of the deflector plate there- 15 above, whereby bullet fragments discharged from said latter plate will be directed clear of said lowermost plate.

3. A bullet stopping device for use with a target 20 to be presented at various elevations to suit the various postures taken by marksmen, said device including an upright support and a deflector plate mounted thereon, a stationary bullet receptacle located beneath the deflector plate, said 25 plate serving to direct bullet fragments into said receptacle, target supporting means carried by the deflector plate, and guide means directly attached to said deflector plate and movable along said upright support for guiding said de- 30 flector plate and target for simultaneous movement along the support, whereby both target and plate may be stationed to accord with the particular posture assumed by the marksman in shooting at the target. 35

ARTHUR D. CASWELL.
